[57] CLAIM

The ornamental design for a line cutting tool, as shown and described.

DESCRIPTION

FIG. 1 is a perspective view of a line cutting tool, showing my new design; the broken line depiction of a fishing rod shaft is for illustrative purposes only, and forms no part of the claimed design;

FIG. 2 is a top plan view thereof;

FIG. 3 is a right side elevational view thereof;

FIG. 4 is a front elevational view thereof;

FIG. 5 is a bottom plan view thereof;

FIG. 6 is a left side elevational view thereof; and

FIG. 7 is a rear elevational view thereof.

FIG. 8 is a right side elevational view of the tool portion of the line cutting tool;

FIG. 9 is a bottom plan view thereof;

FIG. 10 is a front elevational view thereof;

FIG. 11 is a rear elevational view thereof;

FIG. 12 is a right side elevational view of the base portion of the line cutting tool;

FIG. 13 is a top plan view thereof;

FIG. 14 is a front elevational view thereof;

FIG. 15 is a rear elevational view thereof.
